Primary Examiner — Xavier Marti-Santos(74) *Attorney, Agent, or Firm* — Patterson Intellectual Property Law; S. Chase Talbot(57) **CLAIM**

The ornamental design for a hair styling device as shown and described.

DESCRIPTION

FIG. 1 is a top perspective view of a hair styling device showing my new design.

FIG. 2 is a top view thereof.

FIG. 3 is a bottom view thereof.

FIG. 4 is a side elevation view thereof.

FIG. 5 is a side elevation view thereof.

FIG. 6 is a rear elevation view thereof; and,

FIG. 7 is a front elevation view thereof.

The broken lines in the figures are for the purpose of illustrating portions of the hair styling device, which form no part of the claimed design.

1 Claim, 6 Drawing Sheets(56)
